DESIGN FOR A GRAB BUCKET

Bertram J. Bodness, Chisholm, Minn.

Application November 30, 1944, Serial No. 116,629

Term of patent 14 years

(Cl. D41—1)

To all whom it may concern:

Be it known that I, Bertram J. Bodness, a citizen of the United States, residing at Chisholm, in the county of St. Louis and State of Minnesota, have invented a new, original, and ornamental Design for a Grab Bucket, of which the following is a specification, reference being had to the accompanying drawing, forming part thereof.

Fig. 1 is a perspective view of the bucket in open position.

Fig. 2 is a more direct side elevation of the bucket as shown in Fig. 1.

Fig. 3 is a perspective view somewhat similar to Fig. 1 with the bucket in closed position, and

Fig. 4 is a side elevation of the bucket similar to Fig. 2, except that it is in closed position.

I claim:

The ornamental design for a grab bucket, substantially as shown.

BERTRAM J. BODNESS.
